UNITED STATES PATENT OFFICE.

WILLIAM C. CODMAN, OF PROVIDENCE, RHODE ISLAND, ASSIGNOR TO
GORHAM MANUFACTURING COMPANY, OF PROVIDENCE, RHODE
ISLAND.

DESIGN FOR A LETTER-SCALE BASE.

SPECIFICATION forming part of Design No. 37,253, dated December 6, 1904.

Application filed October 26, 1904. Serial No. 230,143. Term of patent 14 years.

To all whom it may concern:

Be it known that I, WILLIAM C. CODMAN, a subject of the King of Great Britain, residing at Providence, in the county of Providence and State of Rhode Island, have invented a new, original, and ornamental Design for a Letter-Scale Base, reference being had to the accompanying drawing.

The figure in the drawing is a face view of my design for a letter-scale base.

What I claim as new, and desire to secure by Letters Patent, is—

The ornamental design for a letter-scale base, as shown.

WILLIAM C. CODMAN.
